F. FORMANECK

REFRIGERATOR

Filed Jan. 15, 1926

2 Sheets-Sheet 2

UNITED STATES PATENT OFFICE.

FRED FORMANECK, OF CHICAGO, ILLINOIS.

REFRIGERATOR.

Application filed January 15, 1926. Serial No. 81,363.

This invention relates to the class of household and like forms of refrigerators having chambered walls, the chambers of which receive the cold drip water from the melting ice 5 used as the refrigerating medium, to resist the passage of exterior heat to the interior of the refrigerator and in consequence maintain said interior at the desired low degree of temperature in an efficient and economical 10 manner. And the present improvement has for its various objects:—

To provide a structural formation and combination of parts in an inner lining or wall for the storage chamber of a refrigerator of the type described, whereby an initial inner downward flow of the cold drip water, and a succeeding outer upward flow of the same is attained, with such flows insulated against heat exchange.

20 To provide in connection with the sub-chamber for such upward flow of the drip water, a vertical drain duct adapted to carry off the surplus and comparatively warm upper strata of water in such sub-chamber.

25 To provide an interengaging sectional formation of the inner lining or walls of a refrigerator of the type described, adapting the same for ready assemblage, disassembly and removal for repair and replacement, all 30 as will hereinafter more fully appear.

In the accompanying drawings:—

Fig. 1 is a perspective view of a household refrigerator to which the invention is applied, the entry doors being shown open 35 and one of the inner vertical casings in a detached condition.

Fig. 2 is in a vertical section of the refrigerator, on line 2—2, Fig. 4.

40 Fig. 3 is a similar view on line 3—3, Fig. 4.

Fig. 4 is a horizontal section on line 4—4, Fig. 2.

45 Fig. 5 is a detail sectional perspective view, illustrating the detail construction of the sectional inner lining or wall of the storage chamber of the refrigerator.

Like reference numerals indicate like parts in the several views.

In the drawings, the invention is shown 50 applied to the ordinary rectangular form of household refrigerator, having rear and side walls 1 and 2 and hinged doors 3 at front, to constitute the outer housing of the article, with the interior of such housing divided by 55 a horizontal orificed partition 4 into a lower storage chamber 5 for food and the like, and

an upper chamber 6 for the reception of a cake of ice used as the cooling medium in the refrigerator. Such construction is old and in general use and may vary in detail 60 construction and association of the parts as the judgment of the constructor, or particular applications, may direct.

In connection with a refrigerator construction substantially as above described, the 65 present invention comprises a hollow and preferably sectional lining or supplementary inner wall for the storage chamber 5 of the refrigerator, constructed as follows:—

A plurality of hollow casings 7, 7' of a 70 flat rectangular shape and of a size complementary to the rear and side faces of the aforesaid storage chamber 5 are formed with offset tongues or flanges 8 at their meeting edges to form interengaging means between 75 the casings when the same are assembled in operative relation, and in the present improvement each casing 7 and 7' is divided by a vertical partition 9 of a heat insulating construction as shown, into a pair of 80 sub-chambers 10 and 11 connected together at their lower ends by a transverse connecting passage 12, with the upper end of the outer sub-chamber 11 having a closed formation while the upper end of the companion 85 and inner sub-chamber 10 is of an open formation adapted to receive the cold drip water as it comes from the melting body of ice in the upper compartment 6 of the refrigerator. To such end the top wall or 90 roof 13 of the storage chamber 5 has a hip form as shown in order to shed the drip water into the sub-chambers 10 of the plurality of casings 7.

With the above described construction and 95 arrangement of parts, the cold drip water fills the two sub-chambers 10, 11, and has a gradual flow down through the sub-chamber 10 and up through the sub-chamber 11 to attain an effective and very economical cooling 100 action on the interior of the storage chamber 5 of the refrigerator, in that the colder drip water in its downward passage in the sub-chamber 10, is next to said storage chamber 5, while the drip water, in a less cold 105 condition, due to absorption of heat, in its upward passage in the sub-chamber 11, acts to prevent inward transmission of heat from the exterior of the refrigerator to the body of cold water passing down through the inner sub-chamber 10.

In actual construction, the excess or spent

drip water may be conducted away in any suitable manner from the top portion of the sub-chambers 11, preferably by means of a single and preferably rectangular pipe or duct 14 arranged in the outer sub-chamber 11 of the rearward casing 7' aforesaid, with the upper end of said outlet pipe 14 having lateral orifices 15 communicating with the sub-chamber 11, while the lower end of said outlet passage 14 is extended through the bottom of the refrigerator for connection with a suitable drain pan or drain pipe of the building.

With the use of a single outlet pipe 14 as above set forth, the upper ends of the sub-chambers 11 in the side casings 7 will have communication with the upper end of the sub-chamber 11 in the rear casing 7' by lateral overflow pipes 16 which extend through adjacent orifices in the walls of the sub-chamber 11 of section 7', to discharge into the same.

Having thus fully described my invention, what I claim and desire to secure by Letters Patent, is:—

1. The combination with the enclosing housing of a refrigerator and the upper ice containing compartment and lower storage compartment of the same, a casing in the storage compartment having a central closed chamber partially surrounded by hollow walls, an insulated partition in said hollow walls dividing the same into inner and outer sub-chambers, with said sub-chambers communicating one with the other at their lower ends, with the upper end of the inner sub-chamber in communication with the ice containing compartment aforesaid and with the upper end of the outer sub-chamber having a closed formation, and means for drawing off the surplus water from the upper end of said outer sub-chamber.

2. The combination with the enclosing housing of a refrigerator and the upper ice containing compartment and lower storage compartment of the same, of an inner lining for said storage compartment formed by a flat casing having a vertical partition of an insulating nature dividing the casing into inner and outer sub-chambers, with said sub-chambers communicating one with the other at their lower ends, with the upper end of the inner sub-chamber in communication with the ice containing compartment aforesaid and with the upper end of the outer sub-chamber having a closed formation, and a vertical drain pipe arranged in the outer sub-chamber and having communication at its upper end with the upper end of said sub-chamber, with its lower end extended through the bottom of the refrigerator for association with a suitable drain.

3. The combination with the enclosing housing of a refrigerator and the upper ice containing compartment and lower storage

compartment of the same, of an inner lining for said storage compartment formed by a plurality of flat casings forming the rear and side walls of the aforesaid storage chamber, each casing having a vertical partition of an insulating nature dividing the casing into inner and outer sub-chambers, with said sub-chambers communicating one with the other at their lower ends, with the upper end of the inner sub-chamber in communication with the ice containing compartment aforesaid and with the upper end of the outer sub-chamber having a closed formation, and means for drawing off the surplus water from the upper end of said outer sub-chamber.

4. The combination with the enclosing housing of a refrigerator and the upper ice containing compartment and lower storage compartment of the same, of an inner lining for said storage compartment formed by a plurality of flat casings forming the rear and side walls of the aforesaid storage chamber, each casing having a vertical portion of an insulating nature dividing the casing into an inner and outer sub-chambers, with said sub-chambers communicating one with the other at their lower ends, with the upper end of the inner sub-chamber in communication with the ice containing compartment aforesaid and with the upper end of the outer sub-chamber having a closed formation, and a vertical drain pipe arranged in an outer sub-chamber and having communication at its upper end with the upper end of said sub-chamber, with its lower end extended through the bottom of the refrigerator for association with a suitable drain.

5. The combination with the enclosing housing of a refrigerator and the upper ice containing compartment and lower storage compartment of the same, of an inner lining for said storage compartment formed by a plurality of separate flat casings formed with interengaging parts on their adjoining ends, said casings forming the rear and side walls of the storage compartment aforesaid, and each casing having a vertical partition of an insulating nature dividing the casing into inner and outer sub-chambers having communication one with the other at their lower ends, with the upper end of the inner sub-chamber in communication with the ice containing compartment aforesaid and with the upper end of the outer sub-chamber having a closed formation, and means for drawing off the surplus water from the upper end of said outer sub-chamber.

6. The combination with the enclosing housing of a refrigerator and the upper ice containing compartment and lower storage compartment of the same, of an inner lining for said storage compartment formed by a plurality of separate flat casings formed with interengaging tongues on their adjoin-

ing ends, said casings forming the rear and side walls of the storage compartment aforesaid, and each casing having a vertical partition of an insulating nature dividing the casing into inner and outer sub-chambers having communication one with the other at their lower ends, with the upper end of the inner sub-chamber in communication with the ice containing compartment aforesaid and with the upper end of the outer sub-

chamber having a closed formation, and a vertical drain pipe arranged in an outer sub-chamber and having communication at its upper end with the upper end of said sub-chamber with its lower end extended ¹⁵ through the bottom of the refrigerator for association with a suitable drain.

Signed at Chicago, Illinois this 12th day of January 1926.

FRED FORMANECK.
